VALVED CONTAINER

Amos Calleson and Edgar A. Calleson, Merrick, N. Y., assignors, by mesne assignments, to Crown Can Company, Philadelphia, Pa., a corporation of Pennsylvania

Application March 8, 1940, Serial No. 323,014

4 Claims. (Cl. 220—24)

The present invention relates to containers and closures therefor of the type having valved openings therein, through which the air in the sealed container may be exhausted, and through which a processing medium, such as steam or a sterilizing gas may be introduced. More particularly, the invention relates to improvements in the structure of the container end member around the opening and the valve, or supplemental closure, disposed therein.

It is a primary object of the present invention to provide an improved valve or closure seat and valve or closure for containers of the foregoing type.

It is a further object of the invention to simplify and cheapen constructions of this kind, while improving the sealing efficiency of the valves and simplifying the valve closing operation.

It is a further object of the invention to provide a construction wherein the valve may be closed by clinching or otherwise distorting a portion of the valve itself, to positively hold the head of the valve upon the valve seat, as distinguished from prior constructions wherein the valves are closed by crimping or distorting the end closure member of the container.

It is a further object of the invention to provide a construction wherein the valve member is clinched upon a valve seat by portions of the valve body disposed on opposite sides of the seat.

In the accompanying drawing, preferred embodiments of the valve and seat are shown, as well as a preferred mechanism for and method of closing the valve, but the invention is not limited to the structural details thereof, except as required by the appended claims.

In the drawing:

Figure 1 is a vertical sectional view of a can end closure member constructed in accordance with the present invention.

Figure 2 is a side elevation of a valve member or supplemental closure, prior to its assembly with the can end.

Figure 3 is a vertical sectional view of an assembled container, closure and valve, with the valve in the open position.

Figure 4 is a similar view with the valve closed, and

Figure 5 is a vertical sectional view of the valve closing or clinching mechanism.

Figure 6 is a fragmentary vertical sectional view, similar to Figure 1, showing a modification, and

Figure 7 is a vertical sectional view of a modified valve member.

The can end member 10 is provided with the usual circumferential seaming flange 11 which is adapted to be double-seamed to the container, preferably after the latter has been filled, in accordance with conventional practice. A sealing compound 12 is disposed in the channel of the flange 11, to provide the usual sanitary seam. The 10 end closure 10 is provided with a central opening 13, defined by a downwardly, inwardly, upwardly and outwardly curled bead 14, providing a downwardly facing, rounded annular valve seat 15. Preferably, substantially the upper half of the bead 14 is provided with serrations or cut-out portions 16, providing lateral passages through the bead. This structure may be made by punching-out an appropriate star-shaped opening in the center of the end closure and 20 then stamping and curling the tangs 17 and the adjacent metal to the form shown in Figure 1.

The valve or closure of the present invention preferably comprises a laterally projecting head 18 and an upwardly projecting tubular neck or body 25 25 19. The head joins the neck along an annular, upwardly facing channel 20, in which a sealing compound 21 is disposed, and the neck 19 fits loosely within the opening 13, while the sealing groove 20 is of the same diameter as the valve 30 or closure seat 15. The valve may be made of any appropriate sheet metal, such as tin-plate, aluminum, or the like.

The valve may be assembled with the end closure member by simply curling the upper end of the neck 19 outwardly and downwardly, after the neck has been inserted in the opening 13, by the use of an appropriate curling die. The bead 25 so formed overlies the bead 14 of the can end closure member and retains the valve loosely in place. Moreover, the bead 25 positions the head 18 in definite predetermined spaced relation below the valve seat 15.

Preferably, the valve and the end closure are assembled in this manner at the can factory and 45 are shipped to the packer detached from the can bodies. The packer fills the can and double-seams the end closure member 10 to the containers in accordance with conventional practice. The filled and closed cans may then be 50 processed in accordance with known methods, such as that disclosed in Patent 1,772,933 Fenn August 12, 1930. In accordance with such processes, air is exhausted from the containers, the containers are inverted and steam under pressure is injected through the valved openings, to

process the contents. The valves are then positively and permanently closed, before the steam has had an opportunity to condense.

The valve of the present invention is particularly adapted for use in this type of process, since it may be permanently closed with great facility by simply continuing the curling of the bead 25, to clinch the bead and the head 18 against the opposite faces of the valve seat.

As shown in Figure 5, this curling or clinching of the bead may be accomplished by a mechanism comprising a plurality of expanding jaw members 28, a jaw expanding plunger 29 and a curling die 30. The expanding jaws 28 are provided with laterally projecting arms 31 slidably mounted in radial ways in a head 32, carried by a vertically movable sleeve 33. The arms 31 are retained in the ways by a plate 34 secured to the head 32 by appropriate screws 35 or the like. The jaws and the arms 31 are urged inwardly to the collapsed position by radially disposed compression springs 36, disposed in appropriate recesses in the head 32 and bearing against pins 37 mounted in the upper ends of the jaws.

The jaws are adapted to be expanded to project the pointed ends 40 thereof outwardly under the annular groove 20 of the valve head by the vertically movable expanding plunger or wedge 29 carried by a vertically movable, centrally disposed rod 38. When expanded, the jaws 28 support the valve against downward movement relative to the seat 15.

The curling die 30 is carried by the lower end of a vertically disposed sleeve 41, movable downwardly relative to the valve holding jaws, after the latter have been expanded. The die terminates at its lower end in an annular curling groove 42, positioned to engage the outwardly and downwardly curled bead 25 (Fig. 3) to impart a further curl thereto, thereby to reduce the length of the neck 19 and to crush or clinch the bead firmly against the upper surface of the bead 14, as indicated at 45 in Figure 4.

The two sleeves 33 and 41, and the rod 38, may be reciprocated in predetermined timed relation by any appropriate mechanism, such as cams, cranks, eccentrics, levers or the like. Preferably, the entire assembly first descends with the jaws in the contracted relation. It should be remembered that, at this time, the valve is disposed in the uppermost position, with the sealing compound 21 and the sealing groove 20 firmly pressed against the valve seat 15, the valve being held in that position by the steam pressure within the container. Hence, the contracted jaws may be lowered to a position where the pointed ends 40 are opposite the laterally projecting portion of the valve head 18. Next, the rod 38 and the expanding wedge 29 carried thereby are lowered, with the result that the cam surfaces on the wedge force the expanding jaws outwardly and project the pointed ends 40 thereof under the sealing groove 20. Then, and while the expanding jaws and the wedge remain stationary, the curling die 30 is forced downwardly by the sleeve 41, whereupon the bead 25 is curled up and crushed somewhat, as indicated at 45 in Figure 4, to tightly clinch the valve head 18 upon the seat 15. The curling die 30 is then lifted by the sleeve 41, the wedge 29 is raised, the jaws 28 are contracted by the operation of the springs 36, and the entire assembly is lifted from the container.

If desired, a plurality of the clinching mecha-

nisms disclosed in Figure 5 may be mounted upon a turret machine, so that a plurality of cans may be sealed simultaneously. In such case, the three relatively movable slides (33, 38 and 41) may be 5 cam-actuated during the continuous or intermittent movement of the turret. If, on the contrary, a single clinching head is to be used, the three slides may be operated conveniently by three cams mounted on a common shaft, so arranged that the lobes thereof are timed to operate the slides in the desired sequence. Since one skilled in the art will readily appreciate the manner in which these elements may be actuated, and since the invention is not limited to 15 any particular means, none are shown in the accompanying drawing.

As stated above, the preferred method of packing and processing foodstuff with the containers of the present invention, is to fill the cans, then 20 seam on the upper valved end member, and then proceed with the vacuumizing, steaming and valve clinching operations. If desired, however, the valved end member may be seamed upon the body at the can-making factory, leaving the bottom 25 end open. In such case, the packer fills the can while inverted through the bottom end and then 30 seams on the bottom end member. In such case, the valve is held in closed position by gravity during the filling operation. After the end member is seamed on, the processing proceeds as 35 above described.

In the modification shown in Figure 6, the can end member is provided with an inwardly and 40 downwardly inclined central wall portion 44, merging at its inner end with an upstanding cylindrical wall 47, thereby providing a groove in the end of the can which will prevent dirt from 45 coming into contact with the bead 14'. Also, the annular bead 14', instead of being provided with serrations or cut-out portions, as in the form in Figure 1, is provided with indentations 16', pressed downwardly in the upper face of the bead. In many cases, these pressed notches are 50 preferred over cut-out portions.

The valve member shown in Figure 7 differs 55 from that of Figure 2 only in that it has a wider and deeper groove 20', which will accommodate a greater volume of sealing compound 21'.

Although the invention has been described with 60 considerable particularity in this specification, and preferred embodiments have been shown in detail in the accompanying drawing, it must be understood that the invention is not limited to such details, but includes all devices and methods coming within the scope of the appended 65 claims and their equivalents.

We claim:

1. A container having a closure provided with an opening for the introduction of a processing medium after the container has been filled, said opening being bounded by an annular seat, and a supplemental closure in the opening, said supplemental closure comprising a hollow, upwardly opening, sheet metal plug disposed loosely in the opening and providing a space between the plug and the opening for the introduction of said medium, said plug having an outwardly flaring lower end disposed in spaced, non-sealing relation under the seat to permit the introduction 70 of the processing medium and an outwardly and downwardly curled upper end above said seat, whereby said supplemental closure may be drawn into permanently closed relation to said seat by inserting a tool into the hollow interior of the plug and curling the upper end thereof down-

wardly against the upper surface of the valve seat.

2. A container having an end member provided with an opening for the introduction of a processing medium after the container has been filled, and a closure for the opening, said opening being defined by an upwardly and outwardly curled bead having passages in its upper surface and an imperforate lower surface constituting a seat for the closure, said closure comprising a neck in the opening, a laterally projecting head below said seat, and an outwardly and downwardly curled upper end overlying said bead, said head and said upper end being spaced apart to permit introduction of said medium through said passages and between the head and said seat, said closure thereafter being adapted to be maintained in permanently closed relation by further downwardly curling the upper end of the neck, thereby reducing the length of the neck and forcing the curled end and head respectively into contact with the upper and lower surfaces of said bead.

3. A container having an end member provided with an opening for the introduction of a processing medium after the container has been filled, and a closure for the opening, said opening being defined by an upwardly and outwardly curled bead having an imperforate lower surface constituting a seat for the closure, said closure comprising a neck disposed loosely in the opening in spaced relation to the margins thereof, a laterally projecting head spaced below said seat and out of contact therewith, and an outwardly and downwardly curled upper end overlying the upper surface of said bead, said head and said

upper end being spaced apart a greater distance than the vertical height of said bead to permit introduction of said processing medium through the space between the neck and the opening and between the head and said seat, said closure thereafter being adapted to be maintained in permanently closed relation by further downwardly curling the upper end of the neck, thereby reducing the length of the neck and forcing the curled end and head respectively into contact with the upper and lower surfaces of said bead.

4. A container having an end member provided with an opening for the introduction of a processing medium after the container has been filled, and a closure for the opening, said opening being defined by an upwardly and outwardly curled bead having an imperforate lower surface constituting a seat for the closure, said closure comprising a neck disposed loosely in the opening, a laterally projecting head spaced below said seat and an outwardly and downwardly curled upper end overlying said bead, said bead and said end being shaped to provide passages for the introduction of said processing medium, and said head and the upper end of the closure being spaced apart to permit introduction of said medium through said passages and between the head and the seat, said closure thereafter being adapted to be maintained in permanently closed relation by further downwardly curling the upper end of the neck, thereby reducing the length of the neck and forcing the curled end and head, respectively, to contact with the upper and lower surfaces of said bead.
